UNITED STATES PATENT OFFICE

NAPOLEON J. PERRY, DECEASED, LATE OF NASHVILLE, TENNESSEE, BY JULIUS W. MARTIN, ADMINISTRATOR, OF NASHVILLE, TENNESSEE, ASSIGNOR TO MAY HOSIERY MILLS, OF NASHVILLE, TENNESSEE, A CORPORATION OF TENNESSEE

STOP MECHANISM FOR KNITTING MACHINES

Original application filed December 22, 1919, Serial No. 346,681. Divided and this application filed August 16, 1922. Serial No. 582,287. Renewed March 31, 1927.

The said invention relates to a stop mechanism for knitting machines and it is an object of the same to provide a stop mechanism adapted to be actuated by improper or exaggerated movements of the sinkers or web-holders in the machine.

A further object of the invention is to provide a device of the character described which will be simple in structure and inexpensive and which may be attached to existing machines without any particular difficulty or expense.

This application is a division of application No. 346,681, filed December 22, 1919, the Patent No. 1,661,485, February 28, 1928.

In the drawings,

Figure 1 is a fragmentary perspective of the invention, and

Figure 2 a plan of a portion thereof with parts broken away.

Referring to the drawings reference character 10 indicates a part of a knitting machine frame having slidably mounted therein a vertical rod 11 which is pressed downward by a spring 12 located between an abutment 13 on the rod and an outwardly extending flange of a bracket 14 secured to the frame 10. The bracket has two outwardly extending flanges having openings in which the rod is 30 slidably mounted, the lower flange having an opening to receive a spline 15 by which rotation of the rod is prevented.

At its lower end the rod 11 is adapted to rest on or strike against a member 16 of the 35 stop mechanism which member in the machine is a part of the means for shifting the belt from a fast pulley to a loose one and vice versa, but which may control or operate a clutch-shifter, an electric circuit breaker, etc., 40 according to the nature of the machine. At its upper end the rod is cut away circumferentially to provide a shoulder adapted to engage over a trip lever 17 pivoted on a support 18. The free end of the lever 17 is adjacent to the sinker cam ring 19 on the rotary 45 head of the machine and is adapted to be moved in a direction to release the rod 11 on being struck by a pin 20. The pin 20 extends upwardly from a lever 21 pivoted at 22 on 50 the sinker cam ring.

In the operation of the device the sinkers 25 are moved in and out in well known manner and should there be any accumulation of yarn at a sinker due to a broken needle or any other cause one or more sinkers will remain in retracted position as indicated at 23 in Figure 2. When in this position the sinkers are adapted to strike against a cam portion 24 of lever 21 and move the same from the dotted line position of Figure 2 to the full line position, in which position it will strike the end of lever 17 and release the rod 11, which is forced down by spring 12 and bears against member 16 to stop the machine.

While the invention is shown on a machine having a stationary needle cylinder, it may evidently be used on a rotary cylinder machine. It is immaterial also whether the sinkers have merely a yarn-sinking function or a web-holding function, or both. It will be 70 obvious to those skilled in the art that various other changes and modifications of the device may be made without departing from the spirit of the invention, the true scope of which is shown in the appended claims.

Having thus fully described the said invention, what is claimed as new and desired to be secured by Letters Patent, is:

1. In a stop mechanism for knitting machines, a rotary element, a lever pivoted thereon at one end, a pivoted trip on a stationary part of the machine, an abutment at the free end of the lever and a cam surface between the ends of the lever for engagement by an abnormally retracted sinker to move said abutment into position to strike said trip, substantially as set forth.

2. In a stop mechanism for knitting machines, a sinker cam ring, a lever of the third class pivoted thereon said lever having a cam between its pivot and its free end positioned for engagement by an abnormally retracted sinker, and means at the free end of the lever operative on the driving mechanism of the machine, substantially as set forth.

3. In a stop mechanism for knitting machines, a sinker cam ring, a lever of the third class pivoted thereon said lever having a cam between its pivot and its free end, a trip

100

on a stationary part of the machine, and means at the free end of the lever for actuating said trip, substantially as set forth.

4. In a circular knitting machine, a series of sinkers, a sinker cam ring controlling said sinkers, a vertically movable rod adapted when moved in one direction to stop the machine, and means for restraining the rod against such movement including an element 10 pivoted on the sinker cam ring and moved by a displaced沉器 in a direction to release said rod, substantially as set forth.

5. In a circular knitting machine, a series of sinkers, a sinker cam ring controlling 15 said sinkers, a vertically movable rod adapted when moved in one direction to stop the machine, and means for restraining the rod against such movement including an element mounted on the cam ring in position to be 20 operated by abnormally retracted sinker to release said vertically movable rod, substantially as set forth.

6. A stop mechanism for knitting machines, comprising a series of sinkers, a sinker cam ring, a cam lever pivoted thereon, a trip device mounted when released to stop the machine, means for restraining said trip device, and means for releasing said trip device including said cam lever which is positioned for engagement by an abnormally positioned sinker, whereby it is moved, said latch released and the machine mechanism stopped, substantially as set forth.

In witness whereof, I have hereunto set 35 my hand at Nashville, Tennessee, this 8 day of August, nineteen hundred and twenty-two.

JULIUS W. MARTIN.
